CLAIM

The ornamental design for an eye cream container as shown and described.

DESCRIPTION

FIG. 1 is a perspective view of an eye cream container, showing my new design, shown with cap shown separated from container in order to show parts not seen when together.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

Broken lines shown in the drawings represent parts of the article that form no part of the claimed design.
